(57) **CLAIM**

The ornamental design for a shower arrangement, as shown and described.

DESCRIPTION

FIG. 1 is a perspective view of a shower arrangement showing my new design.

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines showing of a shower head, controls and hoses is for illustrative purposes only and forms no part of the claimed design.
